[57] CLAIM

The ornamental design for a fluoride-dispensing lollipop, as shown and described.

DESCRIPTION

FIG. 1 is a top perspective view of a fluoride-dispensing lollipop showing my new design;

FIG. 2 is a front elevational view thereof, the undisclosed rear being a mirror image;

FIG. 3 is a left side elevational view thereof, the undisclosed right side being substantially the same;

FIG. 4 is a top plan view thereof.

FIG. 5 is a bottom view thereof.

FIG. 1

FIG. 2

FIG. 5

FIG. 4

FIG. 3
